UNITED STATES PATENT OFFICE.

ADELBERT L. TRAVER, OF PHILMONT, NEW YORK.

MACHINE FOR SEWING LOOPED FABRICS.

1,054,724.

Specification of Letters Patent.

Patented Mar. 4, 1913.

Application filed February 7, 1912. Serial No. 675,919.

To all whom it may concern:

Be it known that I, ADELBERT L. TRAVER, a citizen of the United States, residing at Philmont, county of Columbia, and State of New York, have invented certain new and useful Improvements in Machines for Sewing Looped Fabrics, of which the following is a specification.

The invention relates to such improvements and consists of the novel construction and combination of parts hereinafter described and subsequently claimed.

Reference may be had to the accompanying drawings, and the reference characters marked thereon, which form a part of this specification. Similar characters refer to similar parts in the several figures therein.

Figure 1 of the drawings is a top plan view of a machine embodying my invention adapted for sewing looped fabrics. Fig. 2 is a front elevation of the same. Figs. 3, 4, 5, 6, 7 and 8 are diagrammatic views showing successive positions assumed by the needle, looper and loop-spreader relatively to each other and to the work and work-supporting points in the operation of the machine. Fig. 9 is a top plan view of the loop-spreader detached. Fig. 10 is a view in top plan of a broken away portion of the point-cylinder and the head upon which the same is mounted, showing a stitch-retaining finger or bar overhanging the points.

This invention relates to sewing-machines, and more particularly to a two-thread sewing-machine for sewing looped fabrics, as in attaching knitted cuffs to the sleeves and legs of knitted underwear.

Certain objects of the invention are to facilitate the interlooping of the threads, one with another, to form the seam, and to operate the parts by a more uniform movement, resulting in a more smooth running machine.

Other objects will appear in connection with the following description.

Referring to the drawings wherein the invention is shown in preferred form, 1, is the frame of the machine having the arm, 2, upon which is rotatively mounted the point-cylinder, 3, having the peripherally disposed points, 4, upon which the looped fabrics are impaled in the usual manner. The point-cylinder has fixed thereon the toothed gear, 5, engaged by a pinion, 6, as indicated by dotted lines in Fig. 2, for imparting rotative movement to the cylinder. The pinion, 6,

is in fixed relation to a ratchet, 7, rotatively mounted upon the head, 2^a, of the arm, 2, and adapted to be engaged and intermittently operated by a pawl, 8, whereby a step-by-step rotative movement is imparted to the point-cylinder. A horizontal shaft, 9, is rotatively mounted in bearings upon the frame, 1, and is adapted to be driven by means of a belt-pulley 10. The pawl, 8, is fixed upon the end of an arm, 11, projecting from the strap, 12, of an eccentric, 13, fixed upon the shaft, 9, whereby reciprocating movements are imparted to the pawl, 8, in the operation of the machine.

The stitch-forming mechanism comprises a thread-carrying needle, 14, a thread-carrying looper, 15, a loop-spreader, 16, with means for operating them in proper order and in proper relation to each other and to the points-supported fabric. The needle is fixed upon one end of a lever, 17, pivotally mounted on spindle, 18, upon the arm, 2, and having its other arm connected by a rod, 19, with a strap, 20, of an eccentric, 21, fixed upon the shaft, 9, whereby a reciprocating endwise movement of the needle is induced, the needle being curved and moving in close proximity to the several points, 4, so as to pass through the fabric impaled upon said points, the needle being arranged to point outwardly. The thread, 22, for the needle passes through a tension, 23, fixed upon the spindle, 18, upon which the lever, 17, is pivotally mounted, from which tension it passes over a spring take-up, 24, and through an eye, 25, on the needle-holder on the end of the lever, 17, and thence to the eye of the needle.

The thread-carrying looper, 15, is fixed upon the arm, 26, which projects from a rock-shaft, 27, mounted upon a bracket, 28, projecting from the arm, 2, said rock-shaft having a rocker-arm, 29, connected by a universal joint at, 30, with a rod, 31, projecting from the sleeve, 32, of an eccentric, 33, fixed upon the shaft 9. The rock-shaft, 27, is mounted upon an inclined axis such that its rocking movements cause the looper to reciprocate through a curved path extending transversely of the direction of movement of the needle, the inner end of the looper moving to and fro between a point outside of and above the plane of the point-cylinder, and in rear of the vertical plane of the needle, to a point within and below the top of the point-cylinder, and in front of the ver-

tical plane of the needle, during which movement the inner end of the looper just clears the heels of the points 4.

The thread, 34, for the looper passes through a tension, 35, supported on an arm, 36, fixed upon a spindle, 37, projecting from the frame, 1, from which tension it passes over a ring take-up, 38, through an eye, 39, on the frame of the machine, to the looper which is provided with two eyes, the thread passing from rear to front through the outer eye, 40, and from front to rear through the inner eye, 41, at the inner end or point of the looper.

The loop-spreader, 16, is fixed upon the end of a lever, 42, fulcrumed upon the spindle, 37, and connected by a rod, 43, with the strap, 44, of an eccentric, 45, fixed upon the shaft, 9, whereby reciprocating movements are imparted to said loop-spreader. The end of the loop-spreader, 16, is formed with a thread-engaging notch, 46, and its movements are such that its notched end reciprocates through a curved path extending transversely and just in rear of the path of the needle, and transversely and just in front of the path of the looper. The upward movement of the loop-spreader thus causes its notched end to move from a position below and outside the periphery of the pointed portion of the cylinder, 3, upward and inward to a position above and overhanging the points on the cylinder, during which upward movement its notched end, 46, engages the stretch or loop of needle-carrying thread, between the eye of the needle and the work, and draws out and spreads the same into a loop in the path of the looper, 15, through which spread-loop the looper passes on its inward and downward movement.

By the employment of the loop-spreader, 16, to spread the loop to receive the looper, 15, such latitude is permitted in the timing of the movements of the looper and needle that I am able to operate both the looper and the needle, as well as the loop-spreader, by means of eccentrics mounted upon a common drive-shaft, as shown; and, by the employment of eccentrics to operate each of the elements of the stitch-forming mechanism, I secure great uniformity in their movements, resulting in a very fast and smooth running machine.

From a comparison of Figs. 3 to 8, inclusive, the relative timing of the movements of the needle, looper and loop-spreader, as well as the manner of forming the stitch, will be readily understood. In Fig. 3, the needle is shown at approximately the limit of its forward movement, and the looper near the end of its outward or return movement; and the loop-spreader about midway in its upward movement, a stretch, 34^a, of the looper thread being shown extending from the end-eye of the looper to the work,

47, impaled upon the points 4. Fig. 4 shows no material change in the position of the needle, but the looper is shown at approximately the limit of its return movement, and the loop-spreader at a higher point in its upward movement in engagement with a stretch, 22^a, of the needle-thread extending from the eye of the needle to the work. As the loop-spreader continues its upward movement, leaving the loop or stretch, 22^a, slack, so that the same readily yields to the upward pull of the loop-spreader until the loop, 22^a, is drawn out full in the path of the looper. In Fig. 5, the loop-spreader is shown approximately at the limit of its upward movement, with the loop, 22^a, fully spread, the looper having begun its forward movement, and the needle being near the end of its return movement. In Fig. 6, the looper has moved forward through the spread-loop, 22^a, the loop-spreader has just begun its return movement, and the needle is nearly at the end of its return movement. In Fig. 7, the loop-spreader is shown about midway in its return movement, the spread-loop, 22^a, having been released by the spreader and being left upon the looper. In Fig. 8, the looper is shown at about the limit of its forward movement, the loop-spreader at about the limit of its return movement, and the needle midway in its forward movement, the needle passing just in rear of the looper and in front of the stretch, 34^a, of looper-thread extending from the end-eye 100 of the looper to the work, its point of connection with the work being now somewhat in rear of the path of the needle, due to the feed-movement of the point-cylinder, which feed-movement occurs during the final return movement and the initial forward movement on the needle. The looper begins its return movement and the loop-spreader begins its forward movement at about the same time that the point of the needle enters the work, and the forward movement of the needle and the return movement of the looper are continued until they again reach the position shown in Fig. 3, thus completing the cycle of movements.

I have shown mounted upon a fixed support, as the head, 2^a, of the arm, 2, a stitch-retaining bar or finger, 48, overhanging the points, 4, at and for some distance in rear of the point whereat the stitches are formed. The needle passes below the finger 48, and the looper above said finger, whereby the stitches inserted in the work are caused to embrace said finger. A slight surplus of the threads is thus held by this stitch-retaining finger until the stitches have passed beyond the pulling influence of the stitch-forming mechanism and the tensions, so that as the stitches finally pass off over the end of the finger, 48, they have a slight fullness.

which adds to the elasticity of the seam. The finger, 48, also serves to retain the stitches in the interval between successive pieces of work presented to the stitch-forming mechanism. The finger is adjustably mounted by means of a set-screw, 49, upon a bracket-plate, 50, secured by a screw-bolt, 51, to the head, 2^a, of the arm 2.

What I claim as new and desire to secure 10 by Letters Patent is—

1. In a machine of the class described, and in combination, a cylinder having peripherally disposed points upon which the work is impaled; means for imparting a 15 feed-movement to said cylinder; three stitch-forming elements comprising an outwardly pointed thread-carrying needle, a thread-carrying looper, and a loop-spreader, said looper and said loop-spreader being 20 each movable from a point outside the cylinder transversely of the path of the needle, and said loop-spreader being adapted to engage a loop of the thread carried by one of said thread-carrying elements and spread 25 the same in the path of the other of said thread-carrying elements; and means for operating said stitch-forming elements.
2. In a machine of the class described, and in combination, a cylinder having peripherally disposed points upon which the work is impaled; a drive-shaft; a plurality 30 of eccentrics on said drive-shaft; and three stitch-forming elements operatively connected with the respective eccentrics on said 35 drive-shaft, said elements comprising an outwardly pointed thread-carrying needle, a thread-carrying looper, and a loop-spreader, said looper and said loop-spreader being each movable from a point outside 40 the cylinder transversely of the path of the needle, and said loop-spreader being adapted to engage a loop of the thread carried by one of said thread-carrying elements and spread 45 the same in the path of the other of said thread-carrying elements.
3. In a machine of the class described, and in combination, a cylinder having peripherally disposed points upon which the work is impaled; means for imparting a 50 feed movement to said cylinder; an outwardly pointed thread-carrying needle reciprocatory through the work impaled on

said points; an inwardly pointed thread-carrying looper movable transversely of and in front of the path of the needle; a 55 loop-spreader movable transversely of the path of the needle in rear thereof, and transversely of the path of the looper in front thereof, and adapted to engage a loop of the needle-thread and spread the same in 60 the path of the looper; and means for operating said needle, looper and loop-spreader.

4. In a machine of the class described, and in combination, a cylinder having peripherally disposed points upon which the 65 work is impaled; means for imparting a feed movement to said cylinder; an outwardly pointed thread-carrying needle reciprocatory through the work impaled on said points; an inwardly pointed thread-carrying looper movable transversely of 70 and in front of the path of the needle; a loop-spreader movable transversely of the path of the needle in rear thereof, and transversely of the path of the looper in 75 front thereof, and adapted to engage a loop of the needle-thread and spread the same in the path of the looper; a drive-shaft; a plurality of eccentrics on said drive-shaft; and operating connections between said 80 needle, looper and loop-spreader and the respective eccentrics.

5. In a machine of the class described, and in combination, a cylinder having peripherally disposed points upon which the 85 work is impaled; means for imparting a feed movement to said cylinder; a stitch-retaining finger extending above and transversely of the point whereat the stitch is formed, and a plurality of points in rear 90 thereof; and stitch-forming mechanism including a thread-carrying needle reciprocatory beneath said finger, a thread-carrying looper reciprocatory above said finger, and a loop-spreader reciprocatory on the 95 outer side of said finger adapted to engage a loop of needle-thread and spread the same into the path of said looper.

In testimony whereof, I have hereunto set my hand this 27 day of January, 1912. 100

ADELBERT L. TRAVER.
